Atty.

UNITED STATES PATENT OFFICE

JOHN F. TIBBETTS, OF ATHENS, GEORGIA, ASSIGNOR TO DAVIS & FURBER MACHINE COMPANY, OF NORTH ANDOVER, MASSACHUSETTS, A CORPORATION OF MASSACHUSETTS

CARDING MACHINE

Application filed October 4, 1928. Serial No. 310,249.

This invention relates to a carding machine and may be embodied in either or all of the series of carding machines usually employed in the carding operation but is particularly valuable in the breaker or first carding machine.

The invention has for its main purpose the carding of fibres with which are commingled fibrous materials that are usually carded with great difficulty or not at all in their passage through the carding machine and the removal from the fibre of foreign materials. The invention is particularly valuable in the carding of cotton or wool waste. Such waste is commonly made up of sweepings, waste left on the bobbins or yarn carriers, small bits of cloth and similar fibrous substances which accrue and are collected during the processes of manufacturing yarn and cloth and which, when reduced to fibre, are of very substantial value. The invention is also valuable in the carding of regular or virgin wool or other fibres having commingled therewith clots or bunches or other collections of fibrous material which, if carded to fibre, are of value. In the ordinary carding operation, such various clots, bunches or collections of fibrous material in the form of sweepings, tightly twisted yarn, strings, bits of cloth, etc., pass through the carding operation without being reduced to fibre because very little carding action takes place thereon. Furthermore, the worker roll and the carding cylinder rotate with a great differential in peripheral speed so that the passage of these uncarded materials between the carding cylinder and the worker roll without being taken off by the worker places a great strain upon the teeth of the card clothing theretofore employed. The result not infrequently is to strain, bend, injure and even break the teeth of the card clothing on either or both the cylinder and the workers of the carding machine.

In the present invention the first one or more of the worker rolls of the carding machine, instead of being covered with the usual type of card clothing, are covered with clothing having needle-pointed teeth preferably set at a more acute angle to the roll periphery

and in general of a type of clothing usually employed on nappers and known as napper clothing. Preferably also the backing of the card clothing thus employed on the first one or more worker rolls is thinner and more flexible than that of ordinary card clothing and of the type employed in napper clothing, thus permitting the teeth to yield more readily during the carding operation.

In a carding machine embodying this invention, when the stock is delivered from the feed end to the carding cylinder and arrives at the first worker and stripper unit, the needle-like points of the clothing on the worker roll take hold of and penetrate and remove from the carding cylinder any clots, bunches, pieces of string, tightly twisted yarn, or other fibrous material contained in the stock and carded with difficulty and remove them to the worker roll so that they do not pass on through the carding machine. These materials are then taken by the stripper and returned to the carding cylinder and this process repeated until these materials are carded out. If the stock is of such a character that the first worker and stripper unit does not accomplish the desired result, the worker rolls of one or more succeeding worker and stripper units are equipped with the napper clothing in accordance with the invention so that any of these materials passing the first unit are worked and carded by the succeeding units. There is no strain or injury to the teeth of either the clothing of the carding cylinder or that of the worker rolls because the needle-pointed teeth of the worker rolls penetrate and remove the material and also preferably yield to a substantial extent.

In a carding machine embodying this invention, there is the further advantage that if any seed, straw, burrs, shives or any other foreign material which is not cardable passes in the stock to the carding cylinder, it will be removed by the worker roll and will be forced down toward the base of the teeth of the clothing thereon. This does not take place to any material extent with the ordinary type of card clothing, but with the napper type the fibres are pushed well down on the teeth and

such foreign material is forced thereby down on the base of the teeth where it is held and prevented from being passed back into the stock. Thereafter periodically, as at the end of a day's run, such foreign material is stripped from the worker rolls.

The drawings illustrate diagrammatically an ordinary type of carding machine known as the breaker or first card and this serves to 10 illustrate a preferred embodiment of the invention.

In the drawings:

Fig. 1 is a side elevation in diagrammatic form of a carding machine.

15 Fig. 2 is a side elevation on an enlarged scale of a section of the napper type of card clothing with which the first one or more worker rolls are covered in carrying out the present invention.

20 Fig. 3 is a view similar to Fig. 2 illustrating the ordinary type of card clothing heretofore employed.

As already pointed out, the invention may be applied to any suitable carding machine 25 and the feed end may be of any suitable type. In the construction illustrated, the stock is fed from an endless apron 1 to a familiar type of Garnett breast 2. This Garnett breast is equipped with the usual Garnett flat wire 30 having the familiar saw tooth construction

and this acts to work the stock quite thoroughly. From the Garnett breast the stock is transferred to the carding cylinder 3 and with the type of stock under consideration, 35 there will still be in the stock the materials of a difficult cardable nature already referred to and the uncardable foreign materials already referred to. The carding cylinder 3 is covered with the usual type of card clothing

40 shown generally in Fig. 3 and revolves at a relatively high speed, for example, a common peripheral speed being 1200 feet per minute. The worker and stripper units are shown surrounding the upper segment of the card-

45 ing cylinder each comprising a worker roll 4 and a stripper roll 5. All the various rolls rotate in the direction of the arrows. The first and second worker rolls rotate at a relatively low speed, an ordinary peripheral speed being from twelve to thirteen feet per 50 minute. Ordinarily these worker and stripper rolls are provided with card clothing of the same type as that used on the carding cylinder such as that shown in Fig. 3.

55 In the present invention, the first worker roll 4, and, if necessary, one or more of the succeeding worker rolls are covered with card clothing of the napper type such as illustrated in Fig. 2. In this type of card clothing the points 6 of the teeth are tapered down to the extreme point so that they fairly resemble needle points, whereas in the ordinary type of card clothing, the points 7 are undiminished in cross section and are simply 60 bevelled off at the extreme ends. Further-

more, with the napper type of clothing employed, the points 6 of the napper type of clothing present an angle 8 with respect to the base which is very much more acute than the corresponding angle 9 of the ordinary type of card clothing. Again preferably the 70 backing 10 of the napper type of clothing is considerably thinner and more flexible than the corresponding backing 11 of the ordinary type of card clothing and as the teeth in the napper type have their shanks extending substantially radially of the backing, while in the ordinary type the shanks of the teeth extend diagonally through the backing, the 75 napper type of teeth yield much more readily. 80

It will thus be seen that as the stock on the carding cylinder 3 reaches the worker and stripper unit, any of the difficultly cardable materials in the stock, such as that already referred to, will be caught and penetrated by the sharp pointed teeth of the worker roll extending at a relatively acute angle and removed therefrom to the worker roll. So also any foreign materials will be removed to the worker roll. There will thus be a carding 85 action upon the cardable materials and as they are returned to the carding cylinder partially carded, they will again be removed to the worker roll and thus the carding action will be repeated. 90

95 The foreign materials will be pressed down toward the base of the teeth of the clothing on the worker roll. If the difficultly cardable materials resist the carding action to the extent that some are still carried on by the carding cylinder past the first worker and stripper unit, then the worker roll of the next 100 unit will be equipped with the napper type of card clothing in accordance with this invention, and so on as the conditions may require. 105

Thus the sharp-pointed teeth of the card clothing of the worker rolls equipped in accordance with this invention, the relatively acute angle of these teeth with respect to the base, and preferably also, the relatively thinner and more yielding backing all cooperate to secure the desired action on the stock and are found in practice to enable waste and other fibrous material to be thoroughly carded rapidly and efficiently and without injury 110 to the carding machine. As an example of the results secured by this invention, it has been found that without changing the speed of the carding machine and feeding the same amount of cotton waste of the same quality 115 thereto, the daily production of finished yarn has been increased over one-third. 120

125 It will thus be seen that the series of worker and stripper roll units in the machine is divided into two sections, one of which sections acts first on the material being carded and that the first section, which may comprise one unit or more than one unit as required, has the worker rolls covered with the card clothing such as illustrated in Fig. 2 of the 130

drawings, while the other section has the workers covered with the ordinary type of clothing such as illustrated in Fig. 3 of the drawings.

5 No attempt has been made to illustrate the details of the carding machine and as already pointed out, the invention may be applied to any suitable type of carding machine and to any one or all of a series of carding 10 machines employed. So also none of the usual devices for catching and removing seeds, straws, burrs, shives and other foreign material which fall or drop from the stripper rolls are illustrated, but any such devices may 15 be used as desired.

Having thus described the invention, what is claimed as new, and desired to be secured by Letters Patent, is:

1. A carding machine comprising a feed 20 end, a carding cylinder and a series of worker and stripper roll units divided into two sections, one of which sections acts first on the material being carded and the second of which sections next acts on the said material, 25 and in which the worker roll or rolls of the first section are covered with card clothing having needle-pointed teeth similar to those of napper clothing and in which the worker 30 roll or rolls of the second section are covered with the ordinary type of bevelled end card clothing, whereby material which would ordinarily pass the worker roll or rolls of the first section without being carded is caught and 35 worked thereby and whereby seeds, straw, burrs, shives and other foreign material are caught by the worker roll or rolls of the first section and forced down on the teeth of the clothing thereof.

2. A carding machine comprising the construction defined in claim 1 in which the needle-pointed teeth of the card clothing on the worker roll or rolls of the first section extend at an angle to the roll periphery which is more acute than the angle between the 45 teeth of the clothing of the other workers and the cylinder.

3. A carding machine comprising the construction defined in claim 1, in which the card clothing on the worker roll or rolls of the first section comprises a backing in which the teeth are set which is thinner and more flexible than the backing of the clothing on the remaining worker rolls and cylinder thus permitting the teeth on the clothing on the 50 worker roll or rolls of the first section to yield more readily during the carding operation.

In testimony whereof, I have signed my name to this specification.

JOHN F. TIBBETTS.
